UNITED STATES PATENT OFFICE.

EMANUEL BLAUFORN, OF VIENNA, AUSTRIA.

EXHAUST-STEAM INJECTOR FOR LOCOMOTIVES AND THE LIKE.

Application filed April 24, 1925, Serial No. 25,704, and in Austria May 20, 1924.

This invention relates to exhaust steam injectors of the type which may be operated by exhaust steam and live steam simultaneously as well as with live steam alone, 5 which comprises at least two co-axial cones arranged in series, one of these cones being supplied with live steam alone, while the other is supplied with live steam from the live steam cone and with exhaust steam.

10 Injectors of this kind have a relatively great overall length when compared with ordinary live steam injectors, which is due to the great length of the arrangement of the two steam cones in series and to the circumstance that generally also a number of intermediary cones must be inserted between the exhaust steam cone and the delivery cone. Now it has always been considered to be an essential feature in injectors of this kind, 15 that the axes of the several cones must be strictly coincident to ensure satisfactory working of the injector. The difficulty to fulfil this requirement increases however with the increase of the total constructional 20 length of the injector as the threads and the other bearing and guide faces for the cones must be bored or turned from one and the same side only, to ensure strict axial coincidence of the same. Now a number of tests 25 made with an exhaust steam injector of the kind mentioned have shown, that the strict coincidence of the axes of the cones must exist only between the live steam cone, the exhaust steam cone on one hand and the combining cone and the delivery cone on the other hand while slight deviations between 30 the axes of the aforesaid two series of cones are not vital and do not impair seriously the satisfactory operation of the injector.

35 40 This fact, which we have discovered enables us to construct an injector of the kind specified, with a divided casing, the division of the casing being made in such a manner that each of the two parts contains the nozzles that should have a strict coincidence of 45 the axes. Therefore one part of the casing contains the two steam cones and in some cases the mixing or water cone, while the other part contains the combining cone and 50 the delivery cone. The intermediary cone or cones between the exhaust steam cone and the combining cone may be arranged in the one or the other part of the casing. As the total length of the separate parts of the cas- 55 ings is of course smaller than that of the entire injector the manufacturing of the

threads or guides of the cones that have to be provided with strictly coincident axes is easier and a greater accuracy in the coincidence of the axes of the boreholes or screw 60 threads may be obtained for the several nozzles just at those places, where such accuracy is required.

The accompanying drawing illustrates one constructional embodiment of the invention.

1 and 2 are the two parts of the casing A, which form the body of the injector and may be separately manufactured and fastened or united afterwards as shown f. i. 65 by means of flanges. The part 1 contains the live steam cone 3, the exhaust steam cone 4 and water cone 5, while the second part 2 contains the combining cone and the delivery cone. The intermediary cone 7 arranged 70 between the water cone and the combining cone may either be arranged within the part 1 of the casing as shown in the figure or may be located in the part 2.

What I claim is:

1. An injector of the character described 80 comprising a live steam cone and an exhaust steam cone, a combining cone and a delivery cone, and a casing for said injector cones including two separate parts one of which contains the live steam and exhaust 85 steam cones and the other the combining and delivery cones.

2. An injector of the character described 90 comprising a live steam cone and an exhaust steam cone, a combining cone and a delivery cone, and separable casing parts respectively containing the exhaust steam cone and the combining cone.

3. An injector of the character described 95 comprising a live steam cone and an exhaust steam cone, a mixing cone, a combining cone and a delivery cone, and a casing for said injector including two separate parts, the first of said parts containing the live steam cone and the exhaust steam cone, the second part containing the combining 100 and the delivery cone, and one of these two parts containing the mixing cone.

4. In an injector of the character described 105 a group of supply cones including a live steam cone and an exhaust steam cone, a second group of cones receiving the discharge from the first group of cones, and separable casing parts each housing one of the said groups of cones.

In testimony whereof I affix my signature.
EMANUEL BLAUFORN.
